1,969,862

LATCH MECHANISM FOR CAKE FORMERS
AND THE LIKECharles C. Stilwell, Piqua, Ohio, assignor to The
French Oil Mill Machinery Co., Piqua, Ohio

Application April 3, 1933, Serial No. 664,113

9 Claims. (Cl. 100—51)

This invention relates to improvements in cake formers or machines for compressing oil bearing material into cakes suitable for introduction into the presses by which the oil is expressed from the material, and more particularly to improvements in latch operating mechanisms for the head blocks of such machines.

In a well known type of machine for this purpose, the cakes are formed by pressing charges of meal or oil bearing material in a shallow cake mold to which successive charges of meal are delivered by a travelling charge box arranged to reciprocate over the mold. The cake mold is mounted or formed on the upper end of a vertically movable ram, and the charge is compressed to form the cake between the mold and a head block above the same. The head block is hinged to swing upwardly from its horizontal operative or pressing position over the mold to permit the travel of the charge box over the mold to deposit the charge of meal in the mold, after which the head block is lowered and is held down in its operative pressing position over the mold by a latch. This latch must be released to permit the head block to be again swung up to its raised position for the removal of the molded cake and for the introduction of the next charge of meal into the mold.

An object of my invention is to provide an improved and very simple latch mechanism for the head blocks of such machines which will be durable, efficient and reliable in operation, and of inexpensive construction.

Other objects of the invention are to provide an automatic latch releasing device which is positively operated to release the head block by the return movement of the ram; also to provide an improved latch releasing device which comprises only a single part in addition to the latch itself; also to provide a latch releasing device which normally occupies an operative position and which is rendered inoperative by the movement of the latch to locking position, is returned to operative position for releasing the latch by movement of the mold into its cake pressing action, and releases the latch upon subsequent movement of the mold; also to provide a latch releasing device which has the additional function of cooperating to move the latch to its head locking position.

Various other objects and advantages will be apparent from the following description of an embodiment of the invention, and the novel features of the invention will be particularly pointed out in the appended claims.

In the drawings:

Fig. 1 is a sectional elevation of a cake forming machine equipped with a latch releasing mechanism for the head block embodying my invention, and showing the head block in raised 60 position.

Fig. 2 is a front elevation, on an enlarged scale, of a portion of the machine showing the position of the parts just prior to the movement of the latch to its locking position. 65

Fig. 3 is a fragmentary, similar view showing the position of the parts as the latch is being released.

Fig. 4 is a fragmentary, transverse, vertical section of the machine with the parts in the 70 same position as shown in Fig. 2, taken approximately on line 4—4 of that figure.

Fig. 5 is a similar view showing the parts as the latch assumes its locking position, and prior to the movement of the mold to pressing position. 75

Fig. 6 is a similar view with the head block in locked position and the mold moved upwardly into position for pressing the material.

Fig. 7 is a similar view illustrating the release 80 of the latch for the head block.

In Fig. 1, which illustrates a cake forming machine of known construction, 10 represents the cake mold or form which is supported upon the upper end of, or forms the cap or upper 85 portion of a ram 11 arranged to move vertically in a stationary cylinder 12.

Fluid pressure is admitted to the cylinder for raising the ram and is released therefrom to permit the descent of the ram and mold. Hinged 90 upon a suitable stationary support 14, as by a horizontal pivot 14a, and suitable hinge arms 15, is the head block 16. This head block is adapted to be lowered or swung down from the raised position shown in Fig. 1 to the operative horizontal position over the cake mold shown in Figs. 5 and 6, in which position it is secured by the latch mechanism later described. Any suitable mechanism may be used to actuate the head block in its upward and downward movements, such for example, as a double-acting fluid pressure mechanism shown in part in Fig. 1. This mechanism includes a cylinder 17 stationarily mounted at the rear of the machine, and a piston 18 arranged to reciprocate in the cylinder, and which is provided with an upwardly extending piston rod 19 connected at its upper end as by a link 20 to the rear of the hinge arms 15 of the head block. Pressure fluid is admitted to and discharged from the cyl- 110

inder at opposite ends of the piston 18 by suitable valve or control mechanism, not shown. The admission of the fluid to the lower end of the cylinder beneath the piston acts to raise the piston and lower the head block, and the release of the fluid from the lower end of the cylinder and its admission to the upper end of the cylinder above the piston operates to return the head block to its raised position.

- 10 When the head block has been lowered to its operative or pressing position and has been locked by the latch mechanism, pressure fluid is admitted to the ram cylinder 12 to raise the ram 11 and mold 10 to compress the material between the mold and the head block. After the cake is compressed or molded, the pressure fluid is released from the ram cylinder to permit the ram and mold to descend by gravity to the position shown in Fig. 1, after which the piston 18 is actuated to return the head block to its elevated position.

As thus far described, the cake forming machine is of well known construction, but the invention is applicable to other known or suitable constructions adapted to effect the raising and lowering of the cake mold and of the head block in the manner described.

The latch means shown for releasably securing or locking the head block in its operative or pressing position comprises a pivoted latch or hook 21 depending from a hinge rod or pivot 22 supported in lugs 23 on the forward end of the head block 16, and a stationary keeper or catch plate 24 rigidly secured to the front of the stationary ram cylinder 12. Said keeper is provided in its upper portion with an opening 25 in which the beak or tip 26 of the latch 21 is engageable, as shown in Fig. 6, for locking the head block in pressing position.

40 My improved latch releasing or actuating device, as shown in the drawings, comprises a pendent plate or member 30 provided at its upper end with a bearing lug 31 by which it is supported to swing in a transverse direction upon a horizontal pivot 32 arranged in a forwardly projecting lug or member 33 at the front side of the vertically movable cake mold 10. The member 30 is provided with an integral, laterally projecting cam or curved web-like part 34 which extends from the front edge of the member adjacent the pivot 32, downwardly and inwardly across the face of the member 30 and terminates in a lower edge 35. The cam 34 therefore has an inner face 36 and an outer face 37. The member 30 is also provided at the rear thereof with a stop 38 adapted to abut against the face of the keeper 24 to retain the device in operative position.

60 In the construction illustrated, there are two of the latch releasing devices, one right hand and one left hand, disposed so as to cooperate with the latch at opposite sides thereof. The cam portions 34 therefore preferably extend towards one another as shown. To enable the latch to cooperate with these releasing devices, said latch 21, as shown, is provided at its lower end adjacent the beak 26 with oppositely extending lateral studs or projections 39, each of which, as the latch 21 moves downwardly in the movement of the head block 16 to its operative position, is adapted to engage the upper part of the inner face 36 of the adjacent cam 34. As the downward movement of the latch continues, the studs 39 bearing against the faces 36, cause the latch releasing members 30 to

swing about the pivots 32, so that as the head block 16 assumes its horizontal operative or pressing position, the beak 26 of the latch enters the opening 25 in the keeper 24 and the latch releasing device will be held by the studs 39 in the inoperative position shown in Fig. 5. In this position of the parts, each stud 39 will be disposed adjacent the lower edge 35 of said cam 34. Since the latch releasing members 30 tend to swing inwardly by gravity and since they bear by their cams inwardly against the studs 39 on the latch, this inward pressure supplements the like gravity movement of the latch and therefore aids in moving the latch into holding engagement with the keeper.

80 The ram 11 is now actuated to move the mold 10 upwardly to compress the cake or material in the mold, carrying with it the latch releasing members 30. In this movement the lower edges 35 of the cams 34 will move outwardly over the studs 39 on the latch and pass out of contact therewith at the upper side thereof, thus permitting the latch releasing members to be returned by gravity to operative position with the stops 38 in engagement with the front face of 100 the keeper 24, as shown in Fig. 6. It will be seen that the studs 39 will now be adjacent the lower ends of the outer sides of the cams 34.

90 After the pressing operation has been completed, the pressure fluid in the cylinder 12 is relieved, permitting the ram 11 and mold 10 to descend, and in this movement the latch releasing members 30 are carried downwardly with the mold. The resulting engagement of the outer face of the cams 34 with the studs 39 will urge 110 the lower end of the latch forwardly and disengage the beak 26 thereof from the latch plate 24, since the latch releasing device is held rigidly in position by the engagement of the stops 38 with the face of the keeper 24, the studs 39 115 being therefore forced to follow the outer faces 37 of the cams 34, as shown in Fig. 7. Coincident with this procedure, the pressure has been admitted to the upper end of the head block actuating cylinder 17 to return the head block 16 to 120 its elevated position.

95 While two of the latch releasing devices 30 are preferably employed to equalize the pressure and strain upon the latch, it will be obvious that the invention could be carried out by the use of a 125 single device at one side of the latch.

From the foregoing description it will be seen that the latch releasing device normally occupies an operative position, is rendered inoperative by the engagement therewith of the latch 130 in the downward movement of the latter, is placed in operative position by the upward movement of the mold and releases the latch upon subsequent downward movement of said mold.

135 The device is exceedingly simple, consisting of only a single, relatively simple and inexpensive casting or member which can be made rugged and durable, so that the device will not readily get out of order.

I claim:

1. The combination with a mold and a block which are movable toward and from each other, of a latch movable into position for locking said block in pressing relation to said mold when said block is moved toward said mold, and a latch releasing device which is moved by said latch to an inoperative position when said block is so moved and which, when said mold is moved toward said block, moves to a position in which it will engage and release said latch and un-

- lock said block upon subsequent movement of said mold away from said block.
2. The combination with a mold and a block which are movable toward and from each other, of a latch movable into position for locking said block in pressing relation to said mold when said block is moved toward said mold, and a latch releasing device including a cam which is engaged by said latch when said block is moved toward said mold to cam said device to an inoperative position, and which when said mold is moved toward said block to press the material, moves to a position in which said cam will engage and release said latch to unlock said block upon subsequent movement of said mold away from said block.
3. The combination with a mold and a block which are movable toward and from each other, of a latch carried by said block and movable into position for locking said block when the latter is moved toward said mold, and a movable latch releasing cam carried by said mold and which is engaged by said latch when said block is moved towards said mold and moved thereby to an inoperative position, and said cam, upon movement of said mold toward said block for pressing said material, being movable to a position in which it will engage and release said latch to unlock said block upon subsequent movement of said mold away from said block.
4. The combination with a mold and a block which are movable toward and from each other, of a latch carried by said block and which, when said block is moved toward said mold, moves into position for locking said block in pressing relation to said mold, and a latch releasing cam pivotally mounted upon said mold and normally extending in the path of said latch in said locking movement thereof so as to be engaged and moved thereby transversely out of said path, and upon movement of said mold towards said block to press the material, is moved again into a position in the path of movement of said latch, so as to engage and release said latch upon subsequent movement of said mold away from said block.
5. The combination with a mold and a block which are movable toward and from each other, of a latch having a cam engaging part, said latch being movable into position for locking said block in pressing relation to said mold when said block is moved toward said mold, and a movable latch releasing cam positioned at one side of said cam engaging part of said latch when said block is unlocked and which is engaged by said latch part in said locking movement of said latch and moved to a position such that, upon movement of said mold toward said block to press the material, said cam will shift to the opposite side of said latch part so as to be in a position to engage said latch part and release said latch upon subsequent movement of said mold away from said block.
6. The combination with a mold and a block which are movable toward and from each other, of a latch movable into position for locking said block in pressing relation to said mold when said block is moved towards said mold, and a swinging latch releasing device carried by said mold and which normally rests against an abutment in position to engage said latch in the movement of the latter to locking position, means for shifting said device, during said movement of said latch, to a position to enable said latch to assume its locking position, and said device being then movable upon movement of said mold towards said block to press the material, to a position whereby upon subsequent movement of said mold away from said block said device will engage and release said latch to unlock said block.
7. The combination with a mold and a block which are movable toward and from each other, of a latch on said block movable into position for locking said block in pressing relation to said mold when said block is moved toward said mold, and a movable cam device on said mold which normally occupies a position in which it is engaged by said latch and rendered inoperative upon movement of said block towards said mold, and said device being moved to a position for releasing said latch upon movement of said mold toward said block.
8. The combination with a mold and a block which are movable toward and from each other, of a latch carried by said block and movably mounted to engage and disengage a keeper, a cam device movably mounted on said mold and having different cam faces for engagement with a part of said latch, one of said cam faces acting when said block moves toward said mold to shift said cam device out of latch releasing position and to assist in engaging said latch with its keeper, and said other cam face acting when said mold is moved away from said block to disengage said latch from its keeper.
9. The combination with a mold and a block which are movable toward and from each other, of a latch carried by said block and movably mounted to engage and disengage a keeper, a cam device movably mounted on said mold and having different cam faces for engagement with a part of said latch, one of said cam faces acting when said block moves toward said mold to shift said cam device out of latch releasing position, said cam device being shifted by movement of said mold toward said block to place said other cam face in operative relation to said latch part, and said last mentioned cam face acting when said mold is moved away from said block to disengage said latch from its keeper.

CHARLES C. STILWELL.
